S. HUFFMAN.
REPEATING CANNON.

No. 12,295.

Patented Jan. 23, 1855.

UNITED STATES PATENT OFFICE.

SAMUEL HUFFMAN, OF CHARLESTOWN, ILLINOIS, ASSIGNOR TO S. HUFFMAN
AND D. O. HARE.

IMPROVEMENT IN REPEATING-CANNON.

Specification forming part of Letters Patent No. 12,295, dated January 23, 1855.

To all whom it may concern:

Be it known that I, SAMUEL HUFFMAN, of Charlestown, in the county of Coles and State of Illinois, have invented certain new and useful Improvements in Repeating-Cannon; and I hereby declare that the following is a full, clear, and exact description thereof, reference being had to the accompanying drawings, making part of this specification, in which—

Figure 1 is a top view. Fig. 2 is a longitudinal section. Fig. 3 is a top view with the upper plate and cannon removed. Fig. 4 is a top view of the vent-closing apparatus. Fig. 5 is a vertical transverse section of the same.

The indicating letters refer to the same parts in the different figures wherever they occur.

The nature of my invention consists, first, in the construction and operation of a repeating-cannon, with one muzzle or forward section so arranged as to be capable of being moved forward and backward, with several rear sections attached to a horizontal plate and revolving therewith, as hereinafter described; secondly, in the use of a tank or jacket surrounding the breech of the rear sections, containing cold water for the purpose of keeping the gun cool in rapid firing; thirdly, in an improved apparatus for closing and opening the vent of the gun, which obviates the necessity of using the thumb for that purpose.

Upon a suitable carriage or slide (not shown in the drawings) I place the gudgeons of the upper portion of my gun-carriage, which consists of a circular plate, *a*, with two arms, *b*, extending forward to sustain the sliding forward section or muzzle of the gun *c*. The plate *a* carries on its upper surface three or more friction-rollers, *i*, upon which rest another plate of the same diameter, *d*. These plates are held together by a large pivot-pin, *e*, through their centers, which has a shoulder on its upper portion, which rests on the plate *d*, and a key through it at the under side of *a* being allowed to revolve freely upon the friction-rollers *i*. The plate *a* has a circular concentric projection, *m*, on its upper surface, which fits inside of a corresponding circular concentric flange, *n*, on the under side of *d*, for the purpose of relieving the pin *e* from any undue strain from the recoil of the gun when discharged.

Upon the upper side of the plate *d*, I firmly

secure, by means of bolts through ears cast thereon, five or more rear sections of cannon, *f*, at equal distances from one another and diverging radially. Near the forward end of each of these sections *f* is a projecting flange, *g*. Forward of this the gun tapers slightly to allow of an easier entrance into and more perfect fit in the flange *h* of the forward section, *c*, when the latter is brought back upon a rear section, as hereinafter described. A rack, *l*, is fixed to the under side of the forward section, *c*, and is operated by the pinion *o*. Upon the shaft *t* two lateral projections, *r*, extend from the under side of *c*. V-shaped grooves thereon rest on similarly-shaped ways *s* upon the arms *b*, and thereby support the forward section of the gun *c*. The shaft *t* is operated by a crank-handle, *u*.

A spring-catch, *v*, takes into notches upon the under side of the plate *d* immediately under the center lines of the rear sections. A rock-shaft, *w*, having its bearings at *b*, carries a projecting arm, *x*, which acts upon a prolongation of the catch *v*.

Two spring-catch levers, *y*, are operated by arms *z* projecting forward from the rock-shaft *w*. Their use is to hold the forward section in position against a rear section when the gun is to be discharged.

A jacket, *a'*, is placed round the breech of each of the rear sections, forming a tank or receptacle for cold water, the object of which is to keep the gun and tube cool in rapid firing. There is an opening on the top to admit the water and another on the under side to discharge it when necessary.

The vent-closer, Figs. 4 and 5, is secured upon the gun in any convenient manner, and consists of a cylinder, *a'*, fitting truly in a lower bearing or seat, *b'*, and pressed down thereon by caps *c'*, which may be provided with springs. A vertical projection, *d'*, from the cylinder forms the tube or nipple and a hole bored down through it. The cylinder and the bearing *b'* to the chamber of the gun form the vent.

A lateral projection, *e'*, is a stop to prevent the tube from going beyond the perpendicular in one direction, while it is free to move about one-fourth of a circle in the other when the crank-handle *g'* is elevated. In this position the upper portion of the bore is placed at right angles with the lower portion, thus cutting off

the communication effectually without the use of the thumb, which usual mode of stopping the vent would be inconvenient, if not impracticable, with the revolving sections. This arrangement can be modified to suit the various sorts of priming that may be used.

The end of the projection e' may serve as a sight when elevated.

The gun may be loaded and discharged by seven men (whom I designate by numbers) in the following manner: The section f^2 being loaded and primed, with the forward section, c , brought back until the flange g and the flange h are in contact and the tube d' in its vertical position, No. 1 fires, No. 2 runs c forward until it is disengaged from f^2 , No. 2 at the same time operating the rock shaft w , which releases the spring-catches, then bringing down the crank-handle g' and closing the vent. The disengaged men seize the sections and revolve the plate d in the direction of the dart until the next section, f^3 , arrives in the former position of f^2 , where it is held by the catch v . No. 3 primes and opens the vent, No. 2 runs c back to its first position, and No. 1 fires. No. 4 in the meantime wet-swabs f^2 , and the foregoing movements are repeated until each of the remaining men, stationed opposite the sections, are simultaneously engaged each at his specific duty, which is for No. 5 to dry-swab, No. 6 to load with powder, and No. 7 with ball, the operations of loading and firing by this division of labor being conducted with great rapidity.

My invention presents many advantages over

a single gun worked in the usual manner. It is unnecessary to bring the gun back out of a port or embrasure, the men are not exposed in front, short rammers and swabs are used, the cold water surrounding the breech of each section keeps it cool, and the vent-closer is an important improvement and adds to the security of the men. In cases of emergency the sections may be used independent of the forward one and be discharged in two or more directions simultaneously.

Having thus fully described my improvements, what I claim as my invention, and desire to secure by Letters Patent of the United States, is—

1. The movable forward section, c , with its flange g , in combination with the revolving rear sections, f , secured to the plate d , constructed and arranged substantially as described, and for the purposes specified.
2. The flange n , in combination with the projection m on the plate a , substantially as described, and for the purpose specified.
3. The jacket or cold-water tank a^2 , substantially as described, and for the purpose specified.
4. The vent-closer, Figs. 4 and 5, constructed and arranged substantially as described, and for the purpose specified.

In testimony whereof I have hereunto signed my name this 2d day of January, 1855.

SAMUEL HUFFMAN.
